UNITED STATES PATENT OFFICE

BASIL T. KEHOE, OF BARBERTON, OHIO, ASSIGNOR TO THE BABCOCK & WILCOX COMPANY, OF BAYONNE, NEW JERSEY, A CORPORATION OF NEW JERSEY

SEAM-CALMING DEVICE

Application filed July 9, 1925. Serial No. 42,383.

My invention relates to a device for calking the seams of boilers and the like, as, for example, the seams formed by the butt straps and the boiler shell proper and will best be understood by reference to the accompanying detailed description and annexed drawings in which Figure 1 is an elevational view of an illustrative embodiment of my invention showing same within a boiler drum; Fig. 1^a is an enlarged view of a detail and is taken on line 1—1 of Fig. 1; Fig. 1^b is a section along line 2—2 of Fig. 1^a; Fig. 2 is a view seen from the right of Fig. 1; Fig. 3 is a sectional view taken centrally of the device along line 3—3 of Fig. 1; and Fig. 4 is a view taken on section 4—4 of Fig. 3.

Referring to the drawings by characters of reference 10 denotes generally a carriage or supporting member mounted within the shell 11 of a boiler drum and having opposite wheels 12—12 engaging opposite edges of a butt strap 13 of boiler shell 11. Mounted centrally of the carriage 10 is an upright support 14 bored to accommodate a threaded shaft 15 (Fig. 3). In threaded engagement with shaft 15 is a collar 16 which is seated upon support 14, collar 16 having a bevel gear at its top engaged by a pinion 17, journalled in an arm 17^a on carriage 10 and having a nut 17^b. Shaft 15 may be held in adjusted position by a set screw 19. By turning pinion 17, shaft 15 may be raised or lowered.

As best shown in Fig. 1, the upper extremity of shaft 15 supports a horizontally extending arm 20 at the mid-section thereof. Suspended from each end of arm 20 through mechanism to be described in a pneumatically-operated hammer 21 having a calking tool 22 directed at the proper angle against the longitudinal edge of strap 13. The means by which each hammer 21 is supported and the mechanism for adjusting the position of the hammers to accommodate different sized drums and butt straps, will now be described.

Pivoted at each end of arm 20 is a lever 23 having one end formed of a segment 23^a of a worm wheel engaged by a horizontally disposed worm 24 journalled in a supporting framework 25 also carried upon arm 20. The

disposed bevel gears 26—26, both of which are engaged by a single bevelled gear 27 journalled in an upstanding member 28 and terminating in a squared shank 29 for a wrench or crank. By turning gear 27, both worms 24 will be simultaneously rotated but in opposite directions, and, since the direction of the threads of worms 24 is the same, levers 23 will be rotated in opposite directions. Each lever 23 is joined at its opposite extremity through a pin or pivot 30 to a bell crank 31 having an offset portion 31^a. Removably mounted in each bell crank 31 is one of the air hammers 21 previously mentioned.

Means are provided for adjusting the angular position of a bell crank 31 with reference to a lever 23 joined thereto. To accomplish this I have provided a composite rod 35 having reversely threaded portions 36 and 37 each of which engages in threaded relationship a block 38 pivoted to the off-set portion 31^a of a bell crank 31. It will be apparent that, when rod 35 is rotated, the blocks 38 will be moved either toward or away from one another and that such movement will cause the bell cranks 31 to rotate about pivots 30. This motion combined with the motion of the levers 23 fixing in a general way the horizontal position of the pivots 30 and the up and down motion of supporting arm 20 produced by the turning of collar 16, fixing the general vertical position of said pins, permit adjustment of the position of calking tools 22, not only to accommodate different sized straps, but also to vary with precision the inclination of such tools.

It is desirable that means be had providing for the tools 22 yielding slightly from their adjusted position to accommodate irregularities in the width of the butt strap to be calked. Such means I have shown connecting opposite sections 36 and 37 of rod 35. As shown in Figs. 1, 1^a and 1^b, the inner ends of rod sections 36 and 37 are expanded into heads 36^a and 37^a respectively, which are both contained in a shell 39 the middle portion 39^a of the exterior of which may be of hexagonal shape so as to receive a wrench or the like. Longitudinal keyways 40, 40 are cut in heads 36^a and 37^a each of which receives a flat, elongated

gated U-shaped key 40'. The legs 40' of the U-shaped keys 40' pass through holes in shell 39. A collar 41 threaded to the interior of shell 39 holds the latter in place. A spring 42 tends to press apart the opposing heads 36* and 37*. Thus turning shell 39 turns both sections 36 and 37 of rod 35 which sections however are free to move toward one another against spring 42.

As previously stated, the wheels 12 of carriage 10 are arranged to engage the longitudinal edges of the butt strap 13 and hence serve as a guide for the carriage and to keep the calking tools 22 in their original position. The means of adjusting the gauge of the carriage to accommodate different sized butt straps is shown in Figure 4 and consists of guideways 43 to which are bolted bracket members 44 in which are journaled wheels 12. The bolts 45 pass through slots 46. By loosening bolts 45 brackets 44 carrying the wheels 12 may be moved along guideways 43 and the desired adjustment obtained.

Compressed air is supplied through a flexible hose 47 provided with a valve 48* and connected to a transversely extending pipe 48 which is in turn connected at either end to the hammers 21 by means of flexible conduits 49-49. The air hammers 21 are of a type standard in this art and, since their construction forms no part of the present invention, they have not been described in detail.

In use, the calking device is placed within the boiler drum conveniently by being lifted by suitable means engaging eye 50 in frame 25, the drum 11 being first disposed so as to bring a strap 13 in lower horizontal position. Previously, the gauge of carriage or truck 10 has been adjusted so that the wheels of the latter just straddle the butt strap 13. The device having been placed within the drum, the position of hammers 21 is regulated, if necessary, by means of each of the three adjustments described, i. e. by turning shank 45 causing a rotation of the worm segments 23*, by turning rod 35 to adjust the angular positions of bell cranks 31 about pivots 30 and, by turning nut 17* to regulate the height of transverse arm 20. By means of these adjustments the proper position of the calking tools 22 can be obtained with great accuracy. The carriage is then attached to means for drawing the same through the drum at a constant rate, such means comprising a flexible cord 51 attached to carriage 10 by a hook 52 passing through an eye 53 therein, cord 51 leading to a small motor driven windlass (not shown) outside the drum. After cord 51 has been thus attached the air hammers 20 are set in operation by opening air valve 48* and the movement of the carriage begun by starting the motor operating the windlass drawing in cord 51.

It will thus be seen that my device is entirely automatic in its operation, thereby dis-

placing hand methods which have been customary practice. My improved device achieves many advantages over hand methods of calking the boiler seams. In hand calking the reaction of the air hammer is taken up by the arms and body of the operator, making the work extremely fatiguing and limiting the size of the hammer and the pressure of the air which can be used. In addition, the nature of the work requires the operator to assume a cramped position. Moreover should the angle at which the hammer is held be varied materially (an event which is likely to happen due through fatigue and carelessness on the part of the operator) serious damage to the strap and drum may result.

It will further be observed that by mounting a pair of hammers opposite one another all horizontal components of the reaction will be neutralized, thereby insuring stability of the carriage.

It will be understood that the specific device which has been described in the foregoing is illustrative only and that the same may be widely varied without departing from the spirit of my invention.

I claim:—

1. In a seam calking device, a carriage having guiding means adapted to contact with the butt strap of a boiler drum to maintain the carriage in alignment with said strap and means on said carriage for directing a calking tool against the longitudinal edge of the strap, said guiding means being adjustable transversely of the strap and means for bringing and maintaining said tool in a calking position for different widths of straps and drum sizes, said last named means including means for maintaining said tool in a calking position including a pivoted holding arm for said tool, means for adjusting said arm around said pivot, means adjusting the position of said pivot both horizontally and vertically.

2. In a seam calking device, a carriage, a pair of calking tools mounted upon said carriage, means for adjusting the distance between said tools, and pointing them in different directions, and means for simultaneously raising and lowering said tools.

3. In a seam calking device, a carriage, a pair of calking tools mounted upon said carriage, means for adjusting the distance between said tools and pointing them in different directions, and means for simultaneously raising and lowering said tools, said first named means comprising worm screws and segments.

4. In a butt strap calking device, a carriage, a pair of vibrating calking tools carried by said carriage, means for directing one of said tools against one edge of said strap and the other tool against the opposite edge of said strap, and means for simulta-

neously operating said tools, whereby the opposing components of the reactions of said tools are balanced.

5. In a butt strap calking device, a carriage, a pair of calking tools carried by said carriage, one of said tools being located on one side of said strap and the other tool located on the opposite side of said strap, and means for varying the distance between said tools to accommodate straps of different widths, said tools being opposite one to the other whereby opposing reactions of said tools may be balanced.
